UNITED STATES PATENT OFFICE.

ABRAM C. MOTT, OF PHILADELPHIA, PENNSYLVANIA.

DESIGN FOR A FIRE-PLACE PLATE.

SPECIFICATION forming part of Design No. 16,517, dated February 9, 1886.

Application filed December 30, 1885. Serial No. 187,189. Term of patent 3½ years.

To all whom it may concern:

Be it known that I, ABRAM C. MOTT, a citizen of the United States, residing in Philadelphia, Pennsylvania, have invented a new and original Design for Fire-Place Plates, of which the following is a specification.

My newly-invented design for the wall or lining plates of a fire-place is fully illustrated in the accompanying drawing; and it consists, essentially, of the representation of the interior of a cave or mine.

The side plates, A A, are formed to represent the rough walls of the cave or mine, and the back plate, B, is also formed to represent a continuation thereof, including the representation of three figures of witches grouped around a fire in different positions and bending over a caldron set over the fire.

I claim—

1. The herein-described design for the wall or lining plates of a fire-place, consisting of the representation of the interior of a cave or

mine having a roughened wall-surface, substantially as shown and set forth.

2. The herein-described design for the wall or lining plates of a fire-place, consisting of the representation of the interior of a cave or mine with figures grouped around a fire, substantially as shown and set forth.

3. The herein-described design for the wall or lining plates of a fire-place, consisting of the representation of the interior of a cave or mine with three figures grouped around a fire in different positions and bending over a caldron set over the fire, substantially as shown and set forth.

In testimony whereof I have signed my name to this specification in the presence of two subscribing witnesses.

ABRAM C. MOTT.

Witnesses:

WILLIAM D. CONNER,
HARRY SMITH.
